(57) **CLAIM**

We claim the ornamental design for an angled scalloped bezel luminaire, as shown and described.

DESCRIPTION

FIG. 1 is a top perspective view of an angled scalloped bezel luminaire, showing the new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

The broken line disclosure represents portions of an angled scalloped bezel luminaire which form no part of the claimed design.

1 Claim, 5 Drawing Sheets
